RADIATOR

Reuben H. Keiser, Shamokin, Pa.

Application August 18, 1933, Serial No. 685,781

6 Claims. (Cl. 257—141)

This invention relates to radiators.

An object of the invention is the provision of a radiator which may be used for cooling or heating purposes in which a plurality of spaced fins surround pipes carrying the heating or refrigerating medium, the fins being in the form of spaced plates providing air chambers with the alternate ends of the chambers being closed while the remaining ends are open for the purpose of providing circulation of air through the plates.

Another object of the invention is the provision of a radiator formed of a plurality of thin metal sheets having U-shaped clips for connecting the side edges of the plates together, the U-shaped clips being staggered upon opposite sides of the radiator so that air channels formed between the plates will have one end open and the other end closed.

A further object of the invention is the provision of a radiator having a plurality of radiating fins formed of sheets of metal spaced apart along pipes which carry the refrigerating or heating medium, the sheets being provided with spaced punched lugs which are adapted to be snapped into place through openings in U-shaped members that connect the opposite edges of the plates together, the U-shaped members being staggered upon opposite edges of the plates so that the air channels formed between the plates will have one side edge open and the other closed to provide for a tortuous path for the air which comes in contact with the plates.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claims.

In the drawing:

Figure 1 is a side elevation of a radiator constructed in accordance with the principles of my invention,

Figure 2 is a transverse vertical section taken along the line 2—2 of Figure 1,

Figure 3 is a horizontal section taken along the line 3—3 of Figure 2, and

Figure 4 is a horizontal section taken along the line 4—4 of Figure 2.

Referring more particularly to the drawing, 55 10 and 11 designate a pair of headers which con-

tain a refrigerant or a heating medium and these headers are connected in the usual manner, one with an inlet pipe and the other with an outlet pipe. These pipes are connected either with a heater or a refrigerating apparatus in any well known manner.

Tubular members 12 and 13 are connected to the headers 10 and 11 and are in open communication with the same. Any number of these tubular members may be employed for the purpose. These tubular members provide means for transmission of fluid from one header to the other. The tubular members are removably secured to the headers by means of nuts 14 of well known construction.

The radiating section of the device consists of a plurality of spaced plates 15 and these plates are vertically disposed and located in parallel relation to provide a plurality of air channels 16 and 17. The plates are provided with openings 18 and 19 to snugly receive the tubular members 12 and 13, respectively. The metal around these openings is not entirely cut away but is formed into a plurality of lips 20 which snugly engage the outer walls of the tubular members 12 and 13 and these lips provide inner spacing members for said plates. It will be noted that the lips 20 are located at right angles to the planes of said plates. One side of each face is provided with a plurality of punched-out lugs 25 while the opposite side is provided with punched-out lugs 26. These lugs are stamped out from the body of the plate to provide elliptical openings starting from the maximum point of the elliptical curve and continuing with a parabolic curve to the horizontal surface of the fin plates. Any number of the lugs or burrs may be stamped along the edges of the plate as may be necessary for the purpose.

A U-shaped member, generally designated by 95 the numeral 27 has a bridging portion 28 located between a pair of the plates 15 along the vertical edges of the plates and a pair of returned flanges 29 located in spaced relation with the side flanges 30 of the U-shaped members. Each of 100 the flanges is provided with openings 31 into which are adapted to be snapped the lugs or burrs 26 of one plate and the lugs 32 upon the opposite face of the next adjacent plate. By this means the U-shaped members 27 rigidly secure the side edges of the plates 15 together.

It will be noted, however, that where the bridging portion of the U-shaped member 27 is received between a pair of plates 15 it will substantially close the air space 16 at that end. The 110

opposite end, however, of the space 16 is open to the atmosphere due to the fact that merely the return bent flanges 29 are adjacent each other and are located upon the inner faces of the plates.

In the air channel 17, however, the bridging portion 28 of the U-shaped member 27 is located between the pair of plates 15 and adjacent the open end of the channel 16 while the open 10 end of the channel 17 is located adjacent the closed end of the channel 16. In other words, the closed and open ends of the air channels 16 and 17 are in staggered relation upon opposite sides of the radiator. It will be seen by this 15 construction that the air can enter the channels 16 and 17 upon opposite sides of the radiator but through alternately disposed openings upon opposite sides thereof.

It will be seen by this construction that a 20 large area of radiating surface is provided and a large air capacity is also provided in the air channels 16 and 17 to provide for a large quantity of air passing through the radiator.

I claim:

25 1. A radiator comprising spaced headers, tubular members connecting the spaced headers, a plurality of spaced fin plates having openings, the tubular member being received by the openings, the spaced plates forming air channels, U-shaped members connecting the edges of the plates together, said plates closing alternately disposed ends of the air channels, the end of the channel opposite the closed end being open, and co-operating means on the U-shaped members and plates for locking said U-shaped members on the plate.

30 2. A radiator comprising a spaced headers, hollow members connecting the spaced headers, a plurality of spaced fin plates having openings which receive the hollow members, U-shaped clips connecting the edges of the plates together and maintaining said edges in spaced relation, the clips being so arranged that alternate spaces between the clips have open ends along one side of the radiator while the opposite ends are closed, and co-operating means on the clips and plates for locking the clips on the plates.

35 3. A radiator comprising a pair of spaced headers, a plurality of spaced fin plates located between the headers and provided with openings,

hollow members received by the openings and connecting the headers, U-shaped members having return bent flanges disposed in parallel relation with the outer faces of the legs and connecting the vertical edges of the plates together, an edge of each plate being received between a leg and associated flange of a U-shaped member, and co-operating means on the plates and the flanges for securing the U-shaped members to the plates.

4. A radiator comprising a pair of spaced headers, a plurality of spaced fin plates located between the headers and provided with openings, hollow members received by the openings and connecting the headers, U-shaped members having return bent flanges disposed in parallel relation with the outer faces of the legs and connecting the vertical edges of the plates together, an edge of each plate being received between a leg and associated flange of a U-shaped member, lugs punched from the opposite faces of the plates, the flanges having openings to receive the lugs for securing the U-shaped member to the plates.

5. A radiator comprising spaced headers, 100 spaced plates located between the headers and provided with openings, tubular members connecting the headers and received by the passages, U-shaped members received between a pair of the plates and having return bent flanges, the 105 edge of the plate being located between a leg of the U-shaped member and the associated flange, the flanges having openings, said plates being provided with lugs disposed in the openings.

6. A radiator comprising spaced headers, 110 spaced plates located between the headers and provided with openings, tubular members connecting the headers and received by the passages, U-shaped members received between a pair of the plates and having return bent flanges, the 115 edge of the plate being located between a leg of the U-shaped member and the associated flange, the flanges having openings, said plates being provided with lugs disposed in the openings, the spaces between the plates forming air 120 channels, the U-shaped members being disposed in the ends of the alternate channels for closing said ends, the opposite ends of the channels being open.
